COLLAPSIBLE BOX

Joseph Hirsch Vineberg, Ottawa, Ontario, Canada

Application April 17, 1946, Serial No. 662,877

7 Claims. (Cl. 206—7)

1

This invention relates to one-piece collapsible boxes.

A satisfactory garment-carrying box should have a handle by which the box can be carried and a hanger on which the garment can be supported inside the box. No previous attempt at solving the problem of providing both these elements in a collapsible box of adequate depth all formed out of a single blank has been successful. All prior proposals have been subject to one or both of the disadvantages of excessive waste of material, and a final product which is clumsy and awkward to put together, with the result that, in practice, two piece constructions have been resorted to almost exclusively. Such constructions are, however, expensive compared with one-piece constructions. Thus, the cost of cutting a separate hanger is substantially the same as the cost of cutting a complete box blank, and the cost of securing the hanger to the box, for example by stapling, is also about equal to the cost of cutting out the complete box blank. Since garment-carrying boxes in most cases are not sold to the ultimate user, but are used by stores as a means of packaging their goods to be taken away by the consumer, the expense of the box must be wholly absorbed by the store using it, and is thus a very important item. However, notwithstanding the advantages in principle of one-piece construction, no garment-carrying boxes of such construction have heretofore gone into extensive commercial use.

According to the present invention a one piece garment carrying box is provided which has a handle and a hanger and sufficient depth comfortably to accommodate any garment for the transportation of which the box may be used. This box may be assembled simply and quickly, and when it is in use the strain is so distributed that there is little tendency for the box to pull out of shape or tear.

The one piece box according to the invention comprises essentially a substantially rectangular bottom section and a corresponding top section which are connected along their back edges through an intervening back wall. Side walls are connected along opposite edges of both sections. Connected along the remaining edge of the top section is a top front wall and along the remaining edge of the bottom section is a bottom front wall. A hanger forming member is connected to the outer edge of this bottom front wall and a handle is connected to the outer edge of this hanger member. Slits are formed in both

the front walls running longitudinally thereof and through these slits the handle member is adapted to extend when the box is assembled. Front wall flaps are preferably connected along the front edges of those side walls which are connected to the bottom section, and these flaps are folded to lie along the bottom front wall. They are such that longitudinally extending slits may be formed in them which will register with the slit in the bottom front wall when the flaps are folded to lie along that wall.

The invention will be more fully described with reference to one form of construction illustrated in the accompanying drawings, in which

Figure 1 is a plan view of a blank from which the box is made up,

Figure 2 is a plan view of the front portion of the box in a partly assembled position, and Figure 3 is a perspective view of the front portion of the box in a further stage of assembly,

Figure 4 is a perspective view of the box fully assembled with parts broken away to show the interior arrangement.

25 The box illustrated in these figures comprises a bottom rectangular section 10 and a corresponding top section 11 which are connected to one another along their back edges through an intervening back wall 12. Connected along the 30 sides of the bottom section 10 are side walls 13 and 14 and connected along the sides of the top section 11 are side walls 15 and 16, these side walls being connected to each other and to the back wall 12 by inwardly foldable connecting pieces 17 and 18 of a well-known type. Along the 35 remaining or front edge of the top section 11 is connected a top front wall 19 and along the remaining or front edge of the bottom section

40 10 is connected a bottom front wall 20. To the outer edge 21 of the bottom front wall 20 is connected a hanger forming member 22 and to the outer edge of this hanger forming member is connected a handle member 23. Front wall

45 flaps 25 and 26 extend from the front edges 27 and 28 respectively of the side walls 13 and 14 respectively, these flaps being of a length equal to the combined length of the front wall 20, hanger forming member 22 and handle 23, as indicated in Figure 1, and being thus almost as long as the front wall member 29. Slits 29, 30, 31 and 32 are formed in the top front wall 19, the bottom front wall 29 and the front wall flaps 50 25 and 26 respectively, all these slits being

adapted to register with one another when the box is assembled, as appears from Figure 4.

It will be noted that a fold line 33 runs along the length of the front wall 20 in line with the slit 30 and defines an outer portion 34 of the front wall which is foldable with respect to the remainder or inner portion 34a of that wall. The hanger forming member 22 is formed of two substantially identical parts. The inner of these parts includes a neck portion 35 connecting the outer edge 21 of the bottom front wall 20 to a hanger bar portion 36 and the other part including a neck portion 37 connecting the inner edge 39 of the handle member 23 with a hanger bar portion 38, the two hanger bar portions 36 and 38 being connected to each other along the fold line 40 which is parallel with the slit 30.

The handle member 23 includes a centre portion 41 of a width slightly less than the length of the slit 30 and two wings 45 and 46 of substantially the same width connected to the centre portion along fold lines 47 and 48 respectively, these wings being inwardly foldable on these lines to overlie the centre portion 41. Extending inwardly from the bases of the wings 45 and 46 are tabs 43 and 44 respectively which are of a height substantially equal to the height of the outer portion 34 of the bottom front wall 20, these tabs being folded out when the wings are folded in and so projecting outwardly from the base of the sides of the completed handle member. If desired projecting tabs 49 and 50 may be formed at the outer edges of the wings also, so as to increase the effectiveness of the latter in carrying part of the load of the box. The centre portion and each wing has therethrough an opening 51 of a size sufficient comfortably to accommodate a hand.

The assembly of the box is easily and quickly effected. The first step is to fold in the wings 45 and 46 to overlie the centre portion 41 of the handle. The two parts of the hanger forming member 22 are then folded in toward each other along the fold line 40 and the handle is inserted through the slit 30, the tabs 43, 44, 49 and 50 acting as stops to prevent the handle being inserted too far. The assembly of the box has then reached the stage illustrated in Figure 2.

The next stage is to fold the bottom front wall 20 up at right angles to the bottom section 10 and then to fold the outer portion 34 of the wall 20 at right angles to the inner portion 34a so that this outer portion and consequently the hanger overlie the bottom section and the handle projects out from the bottom front wall (see Fig. 3). The side walls 13, 14, 15 and 16 are then folded up at right angles to the bottom and top sections 10 and 11 respectively and the front wall flaps 25 and 26 are folded in against the bottom front wall, the handle being inserted through the slits 31 and 32 in these flaps. This stage of the assembly is illustrated in Figure 3.

The final stage of the assembly consists in folding the back wall 12 up at right angles to the bottom section 10, folding the top section 11 to overlie the bottom section 10, and folding down the side walls 15 and 16 so that they lie inside the side walls 13 and 14 respectively and are held in this position by the outer portion 34 of the bottom front wall 20 (see Fig. 4). In this process the connecting pieces 17 and 18 are folded inwardly so that they appear in triangular form as shown in Figure 4. When the box is fully assembled, the lid of the box is closed by passing the handle 23 through the slit 29 in the top front wall 19.

I claim:

1. A one piece collapsible box comprising a substantially rectangular bottom section and a corresponding top section connected to one another along their back edges through an intervening back wall, side walls connected along opposite edges of both said top and bottom sections, a top front wall connected along the front edge of said top section, a bottom front wall connected along the front edge of said bottom section, a hanger forming member of greater width intermediate its ends than at either end connected at one end to the outer edge of said bottom front wall, a handle member having a handle opening therethrough connected to the other end of said hanger forming member, and slits in both of said front walls running longitudinally thereof through which said handle member is adapted to extend.
2. A one piece collapsible box comprising a substantially rectangular bottom section and a corresponding top section connected to one another along their back edges through an intervening back wall, side walls connected along opposite edges of both said top and bottom sections, a top front wall connected along the front edge of said top section, a bottom front wall connected along the front edge of said bottom section, slits in both of said front walls running longitudinally thereof, a hanger forming member composed of two substantially identical parts each including a neck portion and a hanger bar portion, said hanger bar portions being connected to each other along a fold line substantially parallel with the slits in the front walls and one neck portion connecting the outer edge of said bottom front wall to one hanger bar portion, and a handle member connected to the other hanger bar portion through the other neck portion, said handle member being of a length less than the length of said slits and being adapted to extend therethrough.
3. A one piece collapsible box comprising a substantially rectangular bottom section and a corresponding top section connected to one another along their back edges through an intervening back wall, side walls connected along opposite edges of both said top and bottom sections, a top front wall connected along the front edge of said top section, a bottom front wall connected along the front edge of said bottom section, slits in both of said front walls running longitudinally thereof, and a fold line in said bottom front wall in line with the slit therein defining an outer portion of said wall foldable with respect to the remainder, a hanger forming member composed of two substantially identical parts each including a neck portion and a hanger bar portion, said hanger bar portions being connected to each other along a fold line substantially parallel with the slits in the front walls and one neck portion connecting the outer edge of said bottom front wall to one hanger bar portion, a handle member connected to the other hanger bar portion through the other neck portion, and tabs of a height substantially equal to the outer portion of said bottom front wall projecting from the base of the sides of said handle member, the length of said handle member being slightly less than the length of said slits whereby said handle member is adapted to extend through said slits and said tabs act as stops to limit the extent of insertion.
4. A collapsible one piece box as defined in claim 3, in which the handle member includes a central portion and two inwardly foldable wings

and the tabs are connected to the inner ends of said wings and are cut out of said central portion.

5. A one piece collapsible box comprising a substantially rectangular bottom section and a corresponding top section connected to one another along their back edges through an intervening back wall, side walls connected along opposite edges of both said top and bottom sections, a top front wall connected along the front edge of said top section, a bottom front wall connected along the front edge of said bottom section, slits in both of said front walls running longitudinally thereof, and a fold line in said bottom front wall in line with the slit therein defining an outer portion of said wall foldable with respect to the remainder, a hanger forming member composed of two substantially identical parts each including a neck portion and a hanger bar portion, said hanger bar portions being connected to each other along a fold line substantially parallel with the slits in the front walls and one neck portion connecting the outer edge of said bottom front wall to one hanger bar portion, a handle member connected to the other hanger bar portion through the other neck portion, tabs of a height substantially equal to the outer portion of said bottom front wall projecting from the base of the sides of said handle member, the length of said handle member being slightly less than the length of said slits whereby said handle member is adapted to extend through said slits and said tabs act as stops to limit the extent of insertion, front wall flaps extending from the front edges of the side walls connected to the bottom section and foldable to lie along said bottom front wall, said flaps being of a length greater than the distance along said bottom front wall from one end thereof to the opposite end of the slit in said front wall, and slits in said front flaps adapted to register with the slit in said bottom front wall when said flaps are folded to lie along said wall.

6. A collapsible one piece box as defined in claim 5, in which the handle member includes a central portion and two inwardly foldable wings and the tabs are connected to the inner ends of said wings and are cut out of said central portion.

7. A one piece collapsible box comprising a substantially rectangular bottom section and a corresponding top section connected to one another along their back edges through an intervening back wall, side walls connected along opposite edges of both said top and bottom sections, a top front wall connected along the front edge of said top section, a bottom front wall, a hanger forming member including two parts each wider at one end than at the other end and connected to each other along their wide ends by a fold line, one of said parts being connected along its narrow end to the outer edge of said bottom front wall, a handle member having at least one handle opening therethrough connected to the other of said parts of said hanger forming member along its narrow end, and slits in both of said front walls running longitudinally thereof through which said handle member is adapted to extend.
